UNITED STATES PATENT OFFICE.

JULIAN ROBERT LINDSEY, OF FORT ROBINSON, NEBRASKA.

BOTTLE.

SPECIFICATION forming part of Letters Patent No. 572,058, dated November 24, 1896.

Application filed January 10, 1896. Serial No. 574,944. (No model.)

To all whom it may concern:

Be it known that I, JULIAN ROBERT LINDSEY, a citizen of the United States, and a resident of Fort Robinson, in the county of Dawes 5 and State of Nebraska, have invented certain new and useful Improvements in Bottles, of which the following is a specification, reference being had to the accompanying drawings, forming a part thereof, in which similar letters of reference indicate corresponding parts.

This invention relates to bottles, jugs, jars, and similar vessels, and the object thereof is to provide a vessel of this class having a neck attachment which is so constructed and arranged that when the vessel has been filled and the neck attachment applied the vessel may be emptied of its contents, but cannot be refilled or reused.

The invention is fully disclosed in the following specification, of which the accompanying drawings form a part, in which—

Figure 1 is a central vertical section of the upper part of a bottle or other vessel provided with a neck and my improved attachment, 25 and Fig. 2 a similar view showing a modified form of construction.

In the practice of my invention I provide a bottle or other vessel A, having a neck attachment B, the lower portion of which is 30 much thicker than the upper portion, and provided at the upper end thereof with an annular valve-seat C, on which is adapted to be seated a valve D, which is cylindrical in form and provided at its upper end with a 35 central vertical bore d, which extends only part way through said valve, and at the lower end of which are formed outwardly-directed perforations d², the lower ends of which, when the valve is seated, are closed by the valve-seat. The neck of the bottle is also provided 40 with an annular shoulder E, in the inner walls of which is formed an annular groove F, and the sides of the valve are also provided with notches or recesses G, which are triangular in form and the larger portions or ends 45 of which are directed downward, and secured to said valve are springs H, the lower ends of which are provided with outwardly-directed arms or projections h, which are adapted 50 to enter the annular groove F.

The annular groove F is of considerable

depth, and the valve is thus given a slight movement within the neck, and when the bottle or vessel is inverted or tilted the valve will leave its seat and pass downwardly in 55 the neck until the outwardly-directed arms h on the springs H strike the upper shoulder or wall of the annular groove F.

The upper end of the neck is adapted to be closed by a plug or stopper K in the usual 60 manner, and the operation will be readily understood from the foregoing description when taken in connection with the accompanying drawings.

In this class of devices the bottle or vessel 65 must first be filled before the neck valve or attachment is applied, and the bottle or vessel A, having been filled with the desired contents, the valve D is inserted into the vessel, as shown in Fig. 1, the springs H being compressed 70 to admit of this operation, and after this the neck or nozzle is closed by the plug or stopper K.

When it is desired to empty the bottle or vessel or to discharge a portion of its contents, the plug or stopper K is removed in the usual manner and the bottle inverted or tilted, when the valve D will leave its seat and drop forwardly or downwardly until the arms or projections h strike upon the upper 75 wall of the annular groove F, and in this position of the valve the contents of the vessel will flow out through the perforations d² and the central bore d, as will be readily understood, and this operation may be repeated or 80 continued until the bottle is entirely empty.

If an attempt be made to refill the bottle by pouring liquids thereinto, the valve D will at once be reseated, when no liquids can enter the bottle, the ports or openings formed 85 by the perforations d² being closed by the valve-seat, and this operation will be the same in any position in which the bottle may be held in an attempt to pour liquids thereinto, and, if desired, the valve D may be 90 constructed as to operate as a float-valve, in which event liquids could not be forced into the bottle.

In the construction shown in Fig. 2 the valve-seat C is also employed, and the valve 95 D is disk-shaped and the lower side of the perimeter thereof is inclined and provided

with the perforations d^2 , and secured within the neck at a short distance above the valve is a cylindrical attachment M, the sides of which are provided with spring-operated 5 plugs m, which are adapted to enter the annular groove F, which in this construction is just large enough to receive them, and the cylindrical attachment M is provided with a central vertical bore m^2 , and in the 10 bottom thereof is formed a cup-shaped cavity or recess m^3 . In this form of construction, when the bottle or vessel is inverted, the contents thereof flow through the perforations d^2 into the cup-shaped cavity or recess m^3 , 15 and through the central bore m^2 of the attachment, and the results produced will be substantially the same as those hereinbefore described. It will thus be seen that I accomplish the object of my invention by means of 20 a device which is simple in construction and comparatively inexpensive, and it is evident that changes in and modifications of the construction herein described may be made without departing from the spirit of my invention 25 or sacrificing its advantages.

In the form of construction shown in Fig. 2 the valve D may also be made to serve as a float-valve, if desired, and in this event the bottle cannot be filled by forcing liquids 30 thereinto, and in an attempt to pour liquids

thereinto the valve D will at once be seated and thus close the neck of the bottle.

Having fully described my invention, I claim as new and desire to secure by Letters Patent—

The combination with a bottle provided with a neck, having an interior annular shoulder and groove and whose lower portion is much thicker than the upper portion, an annular valve-seat in said thicker portion, a 35 cylindrical valve, provided with external triangular notches, adapted to fit on said seat, said valve having a vertical central bore extending partly through it from which extend outwardly - extending perforations whose 40 mouths are located so that they are closed when said valve is seated, springs secured to said valve and having outwardly-directed 45 projections to enter said annular groove, and a stopper in the bottle-mouth, all constructed, 50 located, arranged and adapted to operate substantially as herein shown and described.

In testimony that I claim the foregoing as my invention I have signed my name, in presence of the subscribing witnesses, this 4th 55 day of January, 1896.

JULIAN ROBERT LINDSEY.
